UNITED STATES PATENT OFFICE

BRYCE M. HESS, OF CHICAGO, ILLINOIS

FURNACE STRUCTURE

Application filed September 6, 1929. Serial No. 390,749.

My invention relates generally to furnace structures but, more particularly, to furnaces forming parts of apparatuses for drying materials in general by the use of the products of combustion of the furnaces directly applied to the material, and especially to the drying of grain and the like.

One of my objects is to provide improvements in furnaces to the end that danger of cracking of the walls of the furnace through the exterior surface thereof, will be prevented.

Another object is to provide a construction of furnace a large portion of the walls of which may be made of common non-refractory material and a comparatively small amount of refractory material be required and which will not present danger of the above referred cracking of its walls.

Another object is to provide improvements in drying apparatus of the general character above referred to, to the end of conserving, to the maximum extent, the fuel used in generating the desired heat; and of conditioning to the desired degree the products of combustion supplied to the drying portion of the apparatus, and other objects as will be manifest from the following description.

Referring to the accompanying drawings: Figure 1 is a broken view in vertical sectional elevation of the lower, furnace-equipped, portion of drying apparatus embodying my improvements.

Figure 2 is an enlarged view in vertical sectional elevation of the furnace-equipped portion of the apparatus of Fig. 1, the section being taken at the line 2 on Fig. 1 and viewed in the direction of the arrow.

Figure 3 is a view in front elevation of the furnace of the preceding figures.

Figure 4 is a section taken at the line 4 on Fig. 3 and viewed in the direction of the arrow.

Figure 5 is a section taken at the line 5 on Fig. 4 and viewed in the direction of the arrow.

Figure 6 is a section taken at the line 6 on Fig. 4 and viewed in the direction of the arrow.

Figure 7 is an enlarged view in vertical

sectional elevation of certain of the damper-equipped piping forming a part of the apparatus of Fig. 1.

Figure 8 is a plan section taken at approximately the line 8 on Fig. 4 and viewed in the direction of the arrow; and

Figure 9, an enlarged broken section taken at the line 9 on Fig. 8, and viewed in the direction of the arrow.

In the arrangement shown 8 is a pipe 60 through which the air to be used for drying passes to the structure in which the drying operation is to be effected. The particular construction of such structure of the apparatus is immaterial to the present invention. 65 It may be stated, however, by way of example, that the drying portion of the apparatus may be constructed as shown in United States Letters Patent No. 1,210,166 granted to George H. Hess December 26, 1926, and is 70 disclosed and described in my pending application for United States Letters Patent Serial No. 378,933; filed July 17, 1929.

The furnace, the products of combustion from which are to be utilized for the drying 75 purpose, is represented at 9 and comprises a chamber 10 in which primary combustion, at least, or the fuel supplied thereto, is effected, the front wall 11 of the furnace containing fuel inlet openings 12 controlled by doors 13. 80 The bottom of the chamber 10 is in the form of a grate 14 spaced from the bottom of the furnace to provide a chamber 15 open to the atmosphere at its upper portion through an opening 16 controlled by a door 17 hingedly 85 supported at 18, the wall of the chamber 15 at the lower portion of the latter containing openings 19 controlled by doors 20 and through which the ashes may be removed.

The opposite side walls 21 of the furnace 90 contain lower rearwardly-extending passages 22 opening through the front of the furnace and provided with hingedly-supported doors 23, these passages opening at their rear ends into the lower end of a vertical passage 24 at the rear of, and substantially coincident at its upper portion with, the combustion chamber 10. The lower portion of the passage 24 at its central portion is blocked out as represented at 25, this block- 100

ing out portion, which terminates adjacent the grate 14, presenting upwardly converging walls 26, so that the passage 24 is bifurcated at its lower portion, as indicated at 27 5 at which bifurcation it communicates with the rear ends of the passages 22.

The opposite side walls of the furnace also contain upper passages 28 separated from the passages 22 by the partitions 29 and from 10 the passage 24 by vertical partitions 30 and open at the front of the furnace at which open ends they are equipped with hingedly supported doors 31.

The walls of the combustion chamber 10 15 reach short of the top wall 32 of the furnace whereby there is provided a space 33 into which the passages 24 and 28 upwardly open, namely, along the rear wall and the opposite side walls, respectively, of the chamber 10, 20 the space 33 opening at a point substantially midway between the front and back walls of the furnace, into a flue 34.

The space 33 above the combustion chamber 10 is extended downwardly in front of 25 this chamber as represented at 35 and communicates with a passage 36 in the front wall of the furnace and provided with a hand-controlled damper 37.

In the arrangement shown the flue 34 30 opens into an upwardly extending pipe 38 having a slide valve 39, the pipe 38 being surrounded by a pipe 40 concentric therewith and spaced therefrom this pipe containing series of louvered openings 41 by which the 35 space between the pipes 38 and 40 is caused to be in communication with the atmosphere. The upper end of the pipe 38 is open and the pipe 40 extends upwardly therebeyond and opens upwardly into the pipe 8 through the 40 bottom wall of the latter. A smoke pipe 42 passes through the side of the pipe 40 and opens into the pipe 38, the pipe 42 being provided with a hand-controlled damper 43.

In the arrangement shown the pipe 8 45 communicates at 44 with the atmosphere and means are provided whereby the proportion of hot products of combustion and diluting air are varied to maintain a predetermined temperature in the drying portion of the apparatus.

As the means last referred to form no part 50 of the present invention and are fully disclosed in my said pending application for Letters Patent a brief description thereof will suffice.

The means referred to comprise rotatable dampers 45 located in the pipe 40 above the upper end of the pipe 38 these dampers being connected together at levers 46 thereon by a 60 link 47 for simultaneous operation.

The means referred to also comprise a series of rotatable dampers 48 located in the pipe 8 between the dampers 45 and the inlet 44 and connected together for simultaneous operation by a link 49 connected with

70 levers 50 attached to these dampers. The dampers 45 and 48 are connected together for simultaneous movement by a lever 51 connected with one of the dampers 48 and a link 52 connected with this lever and one of the levers 46, the arrangement of parts just referred to being such that as the dampers 45 move toward closed position the dampers 48 move toward open position, and vice versa.

The damper arrangement just described 75 is controlled by thermostatic mechanism extending into the drying portion of the apparatus and comprising a motor 53 controlled by air pressure supplied to it through a pipe 54 and controlled by the thermostatic device 80 (not shown) in the drying portion of the apparatus, this motor comprising a lever 55 fulcrumed at 56 and connected with a link 57, in turn, connected with a lever 58 on one of the dampers 45. A spring 59 operates, unless restrained, to swing the lever 55 in a direction for moving the dampers 45 to closed position and the dampers 48 to open position.

The air pressure in the pipe 54 causes the 85 lever 55 to assume, in opposition to the tension of the spring 59, the position shown in Fig. 1 in which position the dampers 45 are 90 open and the dampers 48 are closed, when the pressure drops in this pipe, by the rise of 95 temperature in the drying portion of the apparatus above that at which the thermostatic device is set to operate, the spring 59 operates to rotate the dampers 45 toward closed position and the dampers 48 toward open position; and when the temperature in 100 the drying portion of the apparatus drops below that at which the thermostatic device is set to operate, air pressure supplied to the pipe 54 becomes built up therein and moves the dampers 45 toward open position and 105 the dampers 48 toward closed position.

The arrangement also comprises mechanism fully shown and described in my said pending application for patent for automatically closing the pipe 8 to the passage of air 110 thereto through the inlet 44 and the products of combustion and air supplied through the pipes 38 and 40, these means comprising a series of dampers 60 operatively connected with mechanism represented generally at 61 115 which operates normally to hold the damper 60 in open position, but should a temperature condition exist in the drying portion of the apparatus rendering it desirable to permanently close the pipe leading thereto, as for 120 example in the case of spontaneous combustion of the material in the drying apparatus, permits of the automatic movement of the damper 60 to closed position.

It will be understood from the foregoing 125 that by the arrangement of the air passages in the furnace as described the air flowing into the passages 22 travels rearwardly to the back of the furnace and thence upwardly along the back wall of the combustion cham- 130

ber 10 and thence forwardly through the space 33 to the flue 34; and the air flowing into the passages 28 travels rearwardly and upwardly along the side walls of the combustion chamber into the space 33 and thence into the flue 34.

It will further be noted that by the arrangement of the air passages as described the lateral walls and the hot portion of the rear wall of the combustion chamber 10 are separated from the outer walls of the furnace by flues through which the air from the atmosphere flows as stated, with the result of not only maintaining such outer walls in cool condition and thus not subject to cracking by the heat generated in the combustion chamber, but conserving the heat of the furnace by absorption by the air thereby avoiding loss of heat by radiation through the outer walls of the furnace.

The products of combustion discharging from the combustion chamber 10 thus become diluted with relatively cold air entering the furnace through the passages 22 and 28 and such air as may be admitted through the passage 36 and the mixture resulting therefrom discharges into the pipe 38 in a relatively cool condition as compared with the temperature of the discharge were it composed wholly of hot products of combustion issuing from the furnace. Thus the pipe 38 may be made of relatively inexpensive material such as sheet iron without danger of becoming burnt out and particularly when associated with the surrounding pipe 40 through which air from the atmosphere is caused to flow by the suction in this pipe and effect cooling of the wall of the pipe 38, the pipe 40 also serving to reduce radiation of heat from the pipe 38 to the atmosphere by the absorption of heat by the air flowing therethrough and subsequently mixing with the air and products of combustion issuing from the pipe 38.

It will also be noted that the cooling of the products of combustion by dilution with relatively cold air as stated, is effected without impairing the desired combustion of fuel in the combustion chamber 10 as would be the case were the air for cooling the hot products of combustion introduced directly into the combustion chamber 10.

The damper 37 operates to aid in the controlling of the temperature of the mixture of products of combustion and air discharging through the flue 34 and by reason of the adjustable closures 23 and 31 for the passages 22 and 28, the proportion of products of combustion and air supplied through these passages for mixture with the products of combustion may be varied as desired.

As the rear and side walls of the combustion chamber 10, and represented at 10^a and 10^b, are separated from the opposed outer walls of the furnace structure by the air-flues described resulting in the maintenance

of these outer walls in relatively cool condition at all times, these outer walls may be built of relatively inexpensive material such as common brick or cement without danger of cracking, and thus the cost of refractory material required to be used in forming the part of the furnace below the roof thereof, is reduced to the minimum. Economy in the use of refractory material may be practiced in building the roof of the furnace structure as by constructing it as shown in the drawings.

In the arrangement shown the ceiling proper and constructed of refractory material is suspended from the top, or roof portion, 32, of the furnace, the roof portion being made of relatively inexpensive material such as common brick or cement, with a central opening 64 therethrough, the wall of which is stepped as represented at 65 and 66 and opens into a recess 67 in the underside of the roof.

Extending across the recess 67 to the front and rear of the opening 64 and each embedded at three sides thereof in the roof structure 32, are plates 68 and extending along the ends of these plates and embedded in the roof structure are angle irons 69, these angle irons being provided on their horizontal flanges with sets of clips 70 on which I-beams 71 extending crosswise of the furnace and located in the recess 67, are hung, these beams being thus free to expand and contract without unduly stressing the angle irons 69.

The ceiling proper is formed of rows of blocks 72 of refractory material which are hung on the lower flanges of the I-beams 71.

The central opening 64 in the roof is lined with an upper tier of blocks 73 of refractory material flanged at 74 to extend into the stepped portion 65 of the roof proper; and by a lower tier of blocks 75 of refractory material flanged at 76 at which they extend into the stepped portion 66 of the roof proper and rest upon the free edges of the adjacent plates 68, the blocks 75 extending close to the upper surfaces of the adjacent blocks 72 to protect the metal parts of the roof structure from contact with the products of combustion.

The door 17, provided for controlling the amount of air supplied to the fuel in the combustion chamber 10 for effecting combustion, is preferably automatically controlled to diminish the amount of air supplied to the fuel when the temperature in the drying portion of the apparatus reaches a predetermined degree, and to increase the supply of air when the temperature drops below such degree; the arrangement shown for this purpose being the same as that disclosed in my said application for Letters Patent and comprising a cable 62 connected at one end with the door 17 and at its other end with the lever 55, the intermediate portion of the cable extending over pulleys 76 and 77.

While I have illustrated and described a particular construction embodying my invention, I do not wish to be understood as intending to limit it thereto as the same may be variously modified and altered without departing from the spirit of my invention.

What I claim as new, and desire to secure by Letters Patent, is:

1. A furnace comprising side walls and having a combustion chamber the rear wall of which extends in spaced relation to the rear wall of the furnace providing an upwardly extending passage, the lateral walls of said furnace containing passages at the sides of said chamber and of less height than said chamber and communicating at their rear ends with said first-referred-to passage below the upper end of the latter.
2. A furnace comprising side walls and having a combination chamber the rear wall of which extends in spaced relation to the rear wall of the furnace providing an upwardly extending passage, the lateral walls of said furnace containing passages at the sides of said chamber and of less height than said chamber communicating at their rear ends with said first-referred-to passage below the upper end of the latter, the furnace containing a space above said combustion chamber into which said chamber and said first-referred-to passage open and an outlet communicating with said space.
3. A furnace comprising side walls and having a combustion chamber the upwardly extending walls of which at its opposite sides and rear portion are spaced from the ones of said side walls which they, respectively, oppose providing a passage at the rear end of said combustion chamber and passages at opposite sides thereof, partitions in said last-referred-to passages dividing the latter at each side of the furnace into upper and lower passages open to the atmosphere, the lower ones of which open into said first-referred-to passage below the upper end of the latter, the furnace containing a space open to the combustion chamber and to the passage at the rear of said combustion chamber and to said upper passages and also containing a flue communicating with said space.
4. A furnace comprising side walls and having a combustion chamber the rear wall of which extends in spaced relation to the rear wall of the furnace providing an upwardly extending passage, the lateral walls of said furnace containing passages at the sides of said chamber and of less height than said chamber and communicating at their rear ends with said first-referred-to passage below the upper end of the latter and open to the atmosphere, said furnace also having passages at opposite sides of said chamber above said second-referred-to passages and open to the atmosphere, and said furnace con-

taining a space above said combustion chamber into which said chamber and said first-named passage and said last-named passages open.
